ANCHORING MEANS FOR ADJUSTABLE BACKS OF METAL CHAIRS

Howard T. Hallowell, Jr., Rydal, and Frank Bennett, Philadelphia, Pa., assignors to Standard Pressed Steel Co., Jenkintown, Pa., a corporation of Pennsylvania

Application February 2, 1951, Serial No. 209,116

7 Claims. (Cl. 155—157)

1

The present invention relates to occupational chairs, and more particularly to means for horizontally adjusting the back rest of such chairs with respect to the seat.

A primary object of my invention is to provide a generally improved means for adjusting the back support in chairs of the stated type and for maintaining the support positively in adjusted position.

To the latter end the invention contemplates provision of a novel form of clamp, said clamp being positive in action, non-mutilative of the chair parts with which it is immediately associated, readily releasable for adjustment of the back, proof against inadvertent displacement while the back is in normal assembly with the frame of the chair, and susceptible of production at low cost.

In the accompanying drawings,

Fig. 1 is a perspective view of a chair employing clamping means according to my invention;

Fig. 2 is a fragmentary rear perspective view of the chair;

Fig. 3 is a fragmentary sectional view of the seat structure of the chair; and

Fig. 4 is an exploded perspective view of the clamp element.

Referring more particularly to the drawings, the illustrated chair comprises a base structure 10, a seat element 11, and a back rest 12 adjustably mounted on a U-shaped support 14, said support comprising an upper cross piece 15 and two side pieces 16, 16 spaced apart and shaped to extend horizontally under the seat element 11.

The base structure 10 includes a rectangular member secured at its corners to the upper ends 30 of the legs 13 and comprising side members 17 and 18, a front member 19 and a rear member 20. The side members 17 and 18 support the seat element 11, as indicated at 21, 21 in Figs. 1, 2 and 3; and the front and rear members are perforated at 22, 22 and 23, 23 respectively for reception of the horizontal lower end portions 35 of the side pieces 16, 16 of the support member 14.

The support member 14 is anchored in the frame 10 by means of clamps 24, 24 one of which is illustrated in Fig. 4. Each clamp 24 consists of a split sleeve 25 adapted to embrace one of the side pieces 16, said sleeve being provided with radial flanges 26 and 27 one at each side of said split. Near one end, the sleeve is provided with a transverse slot 28 which extends into the flanges 26 and 27 and which is of a width to receive the front member 19 of the

framework. Near the other end, the clamp is provided with mutually-aligned square apertures 29 and 30 located in the flanges 26 and 27 respectively, said apertures being adapted to receive the square shank of a carriage bolt 31. A nut 32 coacts with the threaded shank of the bolt 31, to contract and thereby clamp the sleeve 25 on the side piece 16.

In assembling the back support to the chair, each clamp is engaged with the front member 19, as in Fig. 3, with the sleeve portion 25 registered with one of the perforations 22, whereby the side pieces 16, 16 of the support 14, after insertion through perforations 23, 23 in the rearward member 20, may be passed into the sleeves 25 of the clamps 24 and through the perforations 22, 22 in the forward member 19 to the position, shown in Figs. 1 and 3 for example, wherein the back rest 12 bears a desired relation to the seat 11. The carriage bolts 31 are then tightened to fix the clamps to the side pieces 16, 16 and to thereby anchor the back support 14 in the chair frame. Subsequent adjustment of the back support in a horizontal direction is effected by loosening the nuts 32, sliding the support through the sleeves to the new position, and retightening the bolts.

Obviously, the clamps cannot separate from the assembly until the back support has been removed so that inadvertent displacement of the clamps cannot occur. It will be apparent also that the manner in which the clamp engages the side pieces of the back support and the member 19 of the frame precludes mutilation of either of the engaged elements and insures against functional deterioration.

We claim:

1. In a chair comprising a seat and a back rest, a seat frame having perforated members near the front and the rear of the seat respectively, a support for the back rest having side pieces extending under the seat and freely through the perforations in the back and front members of the seat frame; and a clamp comprising a sleeve 40 split lengthwise and partially opened to loosely embrace one of said side pieces of the back support, said sleeve being formed with radial flanges extending outwardly at each side of said split, and pressure-exerting means associated with said flanges to contract the sleeve on and to thereby anchor the clamp to the side piece, said clamp being provided with a transverse slot adapted 45 for reception of one of the perforated members of the seat frame, said slot intersecting the sleeve 50 and being of sufficient depth to afford registration

of the sleeve with one of the said perforations in the frame member whereby when the side piece of the back support is passed through the perforation and through both parts of the sleeve at the opposite sides respectively of the frame member, and the pressure exerting means is then tightened to contract the sleeve, the clamp will be maintained in interlocking engagement with the frame member and will immobilize the said side piece in the frame.

2. A chair according to claim 1 including a second clamp of the character described arranged to embrace the other side piece of said support and to interlock with the perforated frame member so as to immobilize the side piece with respect to the frame.

3. A chair according to claim 2 wherein each of said clamps interlock with the said front member of the seat frame.

4. A chair according to claim 3 wherein the said slot is in proximity to the end of said clamp which protrudes outwardly from said seat frame.

5. A chair according to claim 1 wherein said flanges are provided with mutually aligned apertures to receive the said pressure-exerting means and wherein further the said means comprises a nut and a bolt coating through said apertures to effect contraction of the sleeve.

6. A clamp comprising a split sleeve, flanges extending outwardly from the split edges of the sleeve, means for forcibly drawing the flanges together to contract the sleeve, and a transverse slot intersecting the sleeve and the adjoining portions of the flanges.

7. A clamp according to claim 6 wherein the flanges are apertured for reception of a bolt, said bolt constituting the means for drawing the flanges together.
